ATTORNEY.

UNITED STATES PATENT OFFICE.

NELLIE S. DAY, OF SPRINGFIELD, MASSACHUSETTS.

DESIGN FOR A DOLL.

50,648.

Specification for Design.

Patented Apr. 24, 1917.

Application filed February 9, 1917. Serial No. 147,717. Term of patent 7 years.

To all whom it may concern:

Be it known that I, NELLIE S. DAY, a citizen of the United States, residing at Springfield, in the county of Hampden and State of Massachusetts, have invented a new, original, and ornamental Design for Dolls, of which the following is a specification, reference being had to the accompanying drawing, forming part thereof.

In the drawings:

Fig. 2 is a side view of a doll showing my new design.

I claim:

The ornamental design for a doll as shown.

N. S. DAY.
